(57) **CLAIM**

The ornamental design for a pole mount, as shown and described.

DESCRIPTION

FIG. 1 is a top, front and right side perspective view of a pole mount showing my new design;

FIG. 2 is a top, rear and right side perspective view thereof;

FIG. 3 is a bottom and front perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 5; and,

FIG. 12 is an enlarged view of portion 12 in FIG. 5.

The broken lines show the features of the pole mount that form no part of the claimed design. The dash-dot-dash broken lines define the boundary of enlarged views and form no part of the claimed design.
